UNITED STATES PATENT OFFICE

EULABEE DIX BECKER, OF NEW YORK, N. Y.

DESIGN FOR A PICTURE FRAME

Application filed December 20, 1928. Serial No. 29,353. Term of patent 7 years.

To all whom it may concern:

Be it known that I, EULABEE DIX BECKER, a citizen of the United States, residing at New York city, in the county and State of New York, have invented a new, original, and ornamental Design for a Picture Frame, of which the following is a specification, reference being had to the accompanying drawing, forming part thereof.

I claim:

The ornamental design for a picture frame, as shown.

EULABEE DIX BECKER.
